VENTILATED SPACER

Samuel P. Crane, 1 Warwick Road, Great Neck, N.Y.,
and Stephen D. Kent, 567 Liberty St., Newburgh, N.Y.

Filed Mar. 23, 1960, Ser. No. 17,161

9 Claims. (Cl. 5—347)

This invention relates to ventilated seat spacers or cushions employing inner coiled wire units and pertains particularly to the casing therefor.

The invention contemplates the provision of a casing having a decorative design in colors applied to selected areas of the open mesh fabric underlying cover of the casing, said cover being provided with an additional outer protecting and wear resisting open mesh, foraminous or net-like cover of suitable relatively inexpensive synthetic plastic material having openings therein of larger dimensions than those of the underlying cover and through which the design is visible.

The invention further contemplates the provision of a ventilating seat spacer casing comprising a pair of ventilating net-like covers secured in face to face relation, the outer cover being formed of plastic having smooth slippery surfaces to permit the user to slide easily on and off the spacer as when getting into or leaving an automobile seat on which the spacer rests, the outer cover serving to protect the coloring material of the design on the underlying cover from abrasion by and from contact with and damage to, the clothes of the user, without loss of ventilating effect.

The invention further contemplates the provision of a casing having an underlying net-like ventilating cover of dimensionally stable material for the inner coiled unit, the cover being optionally smaller than the unit to provide elongated end and edge ventilating openings in the casing and being secured to an outer net-like cover of dimensionally unstable material covering such openings and protecting the underlying cover and anchored thereto against material distortion and changes in size.

The various objects of the invention will be clear from the description which follows and from the drawings, in which

FIG. 1 is a plan view of a ventilating spacer or cushion with parts of the covers and edge binding broken away to show the underlying parts, the dotted lines indicating the stitching.

FIG. 2 is a fragmentary plan view of the two net-like or open mesh covers of the casing showing coloring material applied to an area of the underlying cover.

FIG. 3 is a fragmentary plan view, similar to FIG. 1, of a modified form of the underlying cover, showing it smaller than the coiled unit and showing tabs projecting from said cover into the edge binding.

FIG. 4 is a fragmentary sectional view of the edge portion of the spacer shown in FIG. 1.

FIG. 5 is a similar view of a modified form of the casing wherein the underlying cover terminates in bound or taped edges and ends, in inward spaced relation to the binding of the casing and thereby providing ventilating openings at the sides and ends of the casing.

FIG. 6 is a similar view of another modified form of the spacer, similar to FIG. 5, but wherein the edges of the underlying cover are protected from raveling by a bonding coating of suitable material.

2

FIG. 7 is a similar sectional view taken on the line 7—7 of FIG. 3 and showing the projecting tabs of the underlying cover entering and held within the edge binding.

The wire coiled unit may be of any suitable form but as shown, is of the type disclosed in the Crane Patent No. 2,801,681. In said patent, the flattened coils of rows as 10 and 11 of coiled wire intersect and are interlocked, the rows being formed of a length of coiled wire wound around a thicker border wire as 12. The bottom cover 13 forming the under side of the casing for the unit is of any suitable net-like or other material such as the open mesh fabric heretofore used of twisted paper yarn.

In the present invention, however, the cover which comes into contact with the user of the spacer and which will be termed the "upper" cover, consists of two net-like sheets as 15 and 16, differing considerably in structure, material and function. The underlying sheet 15 of the upper cover may, if desired, be of the same material as that of the bottom cover 13, or it may be of other suitable material which is substantially resistant to permanent distortion, or in other words, is dimensionally stable, such as a textile open mesh fabric of inexpensive yarn not necessarily long lasting nor highly resistant to wear. Whatever the yarn used, it is such that when it is coated with pigmented or coloring material or paint having adhesive properties, the material or paint does not readily peel or wear off.

Selected areas as 17, 18 (FIG. 1) are coated with the paint coating 19 (FIGS. 2 and 4) as by spraying, stencil printing, printing or the like, in any desired design and color combinations for decorative or advertising purposes or the like. The paint, by adhering to the threads of the cover, bonds said threads as 20, 21 together at the intersections thereof and aids to strengthen and to maintain the dimensional stability of the underlying cover, while decreasing only to an immaterial extent, the areas of the openings 22, by reason of the thinness of the coating. The painted areas 17, 18 may be as large or as small as may be desired to produce a practically unlimited range of designs and effects and the entire cover may be like-colored as desired.

Since applied coloring material might stain the clothing of the user as the material wears off under contact with the clothing, and since such material is not usually sufficiently resistant to abrasion to insure that it will be retained by the fabric under the stresses of use of the spacer or cushion, means are provided to protect the paint coating from contact with the user and to take the greater part of the wear and frictional stresses generated as the user sits on the spacer and moves about while seated on 50 the seat section 23 or leans against the back section 24.

Such means takes the form of the net-like or open mesh outer cover 16, preferably of relatively inexpensive synthetic flexible plastic material such as polyethylene or the like. As shown, the sheet forming the cover 16 is extruded or molded in one piece with relatively large openings 25 therein, larger than the openings in the underlying cover 15. When transparent, the outer cover 16 hides only an insignificant amount of the painted areas which are easily visible through the openings 25 and through 55 the transparent cover. When the cover is opaque, the pattern of the casing or design is made frequently even more attractive in appearance.

In any case, the openings 25 permit adequate circulation of air and ventilation. The surfaces of the mesh

sheet 16 are smooth and slippery, whereby the user can slide on to and off the seat without generating a material amount of friction or disturbing the position of the spacer on the seat on which the spacer rests. Such plastic mesh may tend to stretch or distort permanently if permitted to do so under loads, especially if made of inexpensive or relatively thin material with wide openings. To maintain the outer sheet 16 in its proper shape and size, it is anchored to the underlying dimensionally stable sheet 15 in any suitable manner, as by means of suitable stitching 27 which is shown as extending in two diagonal lines across each section 23 and 24 of the spacer.

It will be understood that the lines of stitching may be run in any desired direction and cover any convenient area, and that it may be replaced by suitable adhesive applied between the sheets 15 and 16, or that both adhesive and stitching may be employed to secure the sheets to each other. At the hinge area arranged transversely between the adjacent parts of the sections 23 and 24, the coiled wire unit is omitted, and the upper cover 16 is secured directly to the underlying cover 15 and to the bottom cover 13 as by the transverse line of stitching 29. The edge binding tape 30 is folded in half about those marginal portions 31 of all the covers 13, 15 and 16 which portions project beyond the border wire 12 and are stitched together and to the binding tape by the stitching 32. Such marginal portions may extend downwardly and outwardly past the border wire so that the lowermost edge of the binding is normally below the bottom cover 13 (FIGS. 4-7). The thus bound marginal portions of the casing are biased to a position in angular relation to the plane of the upper cover and are relatively stiff though yieldable. Said portions add some resilience to the spacer and at times permit air to pass thereunder and between the spacer and the seat or back as the user moves about and compresses one part of the portions 31 to cause another part to rise under the resulting tilting action. Since such portions are biased out of the plane of the upper cover, they cannot interfere with the sliding movement of the user on to or off the spacer.

In the forms of the invention shown in FIGS. 3, 5, 6 and 7, the underlying cover is made smaller than the inner wire unit to provide elongated openings 33 in the upper part of the casing between the edges of the underlying cover and the adjacent inner edges of the binding 30, the openings being partly covered only by the outer cover 16. To insure against raveling of the marginal portions 34 of the underlying cover 35 of FIG. 5, said portions are enclosed all around said cover within a second binding tape 36 stitched thereto by the stitching 37 in the same manner as the binding 30 is secured. Air readily passes through the openings 33 for ventilating purposes without interference by the cover 35.

As shown in FIG. 6, the binding tape 36 is omitted and replaced by a coating of suitable bonding material 38 such as shellac, lacquer or the like, to hold the threads together against raveling and to form a sort of selvage on the cover. The coating may be applied in any suitable manner as by spraying, stencilling, dipping or the like.

In FIGS. 3 and 7 are shown tabs as 39 which project outwardly at intervals from the edges of the underlying cover 40 across the openings 33 and enter and are secured within the binding tape 30 to insure against any undesirable shifting of the upper cover which might possibly occur. The edges of the underlying cover may be sealed against raveling as hereinbefore described, the coating 38 being illustrated in FIG. 7 for that purpose.

It will now be seen that by the use of a plastic open mesh auxiliary or additional cover for the casing, it becomes possible safely to decorate the underlying cover and to protect not only the decorated areas but also the underlying cover throughout against wear; that by anchoring to each other the sheets constituting the upper cover, the dimensional stability of the cover is preserved; that additional elongated and relatively wide edge openings are provided if desired, to aid ventilation and that the intended

purposes of the invention have been adequately attained.

While certain specific forms of the invention have herein been shown and described, various obvious changes may be made therein without departing from the spirit of the invention defined in the appended claims, such as the use of open mesh ventilating sheets of any type or material for any of the covers, and the use of any suitable inner spacer unit whether coiled or of wire or other material or form.

We claim:

1. In a ventilating spacer, an inner unit and a casing for the unit, the casing comprising an inner open mesh sheet, selected pigmented areas on the sheet constituting decoration, and an outer mesh protecting sheet, the inner sheet being smaller than the outer sheet and having the edges thereof arranged in inward spaced relation to the respective adjacent edges of the outer sheet to provide elongated ventilating spaces between the edges of the inner and outer sheets, the spaces being covered in part only by the outer sheet, the openings in the mesh of the outer sheet being sufficiently large to expose the greater parts of the pigmented areas to view.
2. The ventilating spacer of claim 1, the marginal portions of the decorated sheet being sealed against raveling.
3. The ventilating spacer of claim 1, spaced apart tabs projecting outwardly at intervals from the decorated sheet between adjacent elongated spaces and means securing the tabs to the adjacent parts of the outer sheet.
4. The ventilating spacer of claim 3, the inner unit including a border frame, the edges of the inner sheet between the tabs being free, the securing means being binding tape enclosing the marginal parts of the outer sheet and the tabs and biasing said parts into angular relation to the general plane of the sheet.
5. In a ventilating spacer, having an inner coiled wire unit, a bottom cover for the unit, an upper cover for the unit and means securing the marginal portions of said covers together, the upper cover comprising two open mesh sheets arranged in face to face relation, the outer sheet being of synthetic flexible plastic material having ventilating openings therethrough and constituting a protecting and wearing cover, and the other underlying sheet being of fabric having smaller ventilating openings therethrough and pigmented spaced apart selected areas on the underlying sheet constituting decorations visible through the openings of the outer sheet and protected by said outer sheet against wear and abrasive deterioration when the spacer is in use.
6. The ventilating spacer of claim 5, the outer sheet being anchored to the underlying sheet to secure dimensional stability thereof and having smooth slippery surfaces.
7. The ventilating spacer of claim 5, the underlying sheet having intersecting threads and being dimensionally stable, the coating being thin and bonding the threads together at the intersections thereof in said selected areas, the openings in the underlying sheet at said areas remaining open.
8. A ventilating spacer comprising an inner spacer unit comprising a border wire frame and shaped members secured to the frame, and a ventilating casing for said unit, the casing comprising an inner sheet of open mesh fabric, a coat of coloring material arranged at selected areas of the sheet and decorating said areas, and an outer open mesh flexible sheet extending beyond the frame and superimposed on the inner sheet, the decorated areas of the inner sheet being visible through the outer sheet and being protected thereby against wear and against contact with the body of the user of the spacer, the outer sheet being of sufficient thickness for such protection.
9. In a ventilating spacer, an inner air-permeable spacer unit, a ventilating cover for the unit having a multiplicity of closely spaced apart ventilating openings therein and comprising a pair of sheets arranged in face to face relation, the outer one of the sheets having relatively large openings therethrough and constituting a protecting and wearing cover, the other underlying one of the sheets hav-

ing openings therethrough substantially smaller than the openings of the outer one of the sheets, pigmented areas at selected points of the underlying sheet constituting decorations visible through the openings of the outer sheet and protected by the outer sheet against wear and abrasive deterioration when the spacer is in use, the outer sheet being of sufficient thickness for such protection, and means for holding the unit and the cover together, the underlying sheet having intersecting threads and a thin pigmented coating at said selected points bonding together 10 the threads of said areas at the intersections thereof.
